[57] CLAIM

The ornamental design for a boat, as shown and described.

DESCRIPTION

FIG. 1 is a side elevation of a boat showing my new design.

FIG. 2 is a plan view of the same.

FIG. 3 is a bottom view of the same.

FIG. 4 is a front end view of the same.

FIG. 5 is a rear end view of the same.
